UNITED STATES PATENT OFFICE.

JACOB VELTUNG AND ERNEST VELTUNG, OF NEW YORK, N. Y.

HORSE-COLLAR.

SPECIFICATION forming part of Letters Patent No. 781,383, dated January 31, 1905.

Application filed January 27, 1902. Renewed July 20, 1904. Serial No. 217,299.

To all whom it may concern:

Be it known that we, JACOB VELTUNG and ERNEST VELTUNG, citizens of the United States, and residents of New York city, in the county of New York and State of New York, have invented a certain new and useful Improvement in Horse-Collars, of which the following is a specification.

The present invention relates to horse-collars wherein there is a wearing-piece to which pads or cushions are secured, the objects of the invention being to avoid certain objectionable features which exist in a wooden wearing-piece as heretofore constructed and at the same time to reduce the cost.

The present invention is more particularly intended for use in connection with air-cushions such as are shown in Letters Patent of the United States granted October 29, 1901, and bearing number 685,541, though it may be used in combination with cushions or pads of other known construction or kind. The horse-collar illustrated in said patent includes a wooden wearing-piece which is carved or formed from one piece. Such a wearing-piece is liable to warp and split and is also expensive to make.

According to the present invention liability to warping and splitting is avoided and durability and strength retained or even increased by making the rear wale of wood veneer several plies thick and securing a fore wale, preferably of wood, thereto in any suitable manner. The cushions are secured to the collar in appropriate ways, the collar being first waterproofed, if desired.

The preferred form of the invention is illustrated in the accompanying drawings, forming part hereof, in which—

Figure 1 is a perspective view of the finished wearing-piece; Fig. 2, a cross-section on the line $\alpha\alpha$ of Fig. 1, and Fig. 3 a cross-section on the line $\gamma\gamma$ of Fig. 1.

In the preferred manner of carrying out the present invention the fore wale α is carved or otherwise formed from wood, being provided, preferably, with a groove b at the rear side thereof and having its inner edge curved or concaved to receive the outside of the bowl-shaped rear wale c , which is made of wood veneer several plies thick, said rear wale being in one piece and having the opening d in

it to go over the animal's head. The two wales are secured together in any suitable manner, as by nails, screws, &c. It is remarked that 55 the veneer rear wale is conveniently formed in dish shape by dies in a veneer-press and that it is more convenient to make it without any central opening, the said opening being made afterward by sawing or cutting along 60 the edge e after the front and rear wales are secured to each other. The rear edge f of the rear wale may be made by sawing or cutting in like manner. The rear wale is therefore convex on the outside and concave or 65 dished on the inside, and the hame's rest against the wearing-piece in or adjacent to the groove b . Air-cushions or other forms of pads are to be secured to the wearing-piece on the inside thereof. In case the air-cushions described in said Letters Patent are used they may be secured in place as in said patent described. It is to be understood that the veneer has the grain of the wood crossing as usual, thus giving strength and preventing warping. 75

The wearing-piece may be varnished, waterproofed, or otherwise treated before the cushions or pads are put on to finish the collar.

What is claimed as new is—

1. In a horse-collar, a fore wale combined with a wood-veneer concave rear wale, substantially as described.
2. In a horse-collar, a wearing-piece comprising a fore wale provided with a groove at its rear, combined with a concave wood-veneer 85 rear wale secured to the inside of the fore wale, substantially as described.
3. In a horse-collar, a wearing-piece comprising a fore wale combined with a wood-veneer rear wale said rear wale being concave 90 on the inside and convex on the outside, substantially as described.

4. In a horse-collar, a wearing-piece comprising a fore wale of wood combined with a concave wood-veneer rear wale secured to the 95 inner side thereof, substantially as described.

Signed at New York city, in the county of New York and State of New York, this 25th day of January, A. D. 1902.

JACOB VELTUNG.
ERNEST VELTUNG.
